Primary Examiner — Brian N. Vinson(74) *Attorney, Agent, or Firm* — Avyno Law P.C.(57) **CLAIM**

I claim the ornamental design for a flicker candle, as shown and described.

DESCRIPTION

FIG. 1 is a front perspective view of a flicker candle.

FIG. 2 is a rear view of the flicker candle of FIG. 1.

FIG. 3 is a front view of the flicker candle of FIG. 1.

FIG. 4 is a side view of the right side of the flicker candle of FIG. 1.

FIG. 5 is a side view of the left side of the flicker candle of FIG. 1.

FIG. 6 is a top view of the flicker candle of FIG. 1; and, FIG. 7 is a bottom view of the flicker candle of FIG. 1.

The broken lines shown are included for the purpose of illustrating the unclaimed portions of the article and form no part of the claimed design.
